UNITED STATES PATENT OFFICE.

BRYANT L. AKINS, OF BROOKLYN, NEW YORK.

EMBOSSING-PRESS TYPE AND STRIP HOLDER.

Application filed April 11, 1925. Serial No. 22,254.

To all whom it may concern:

Be it known that I, BRYANT L. AKINS, a citizen of the United States of America, residing at Brooklyn, Kings County, and 5 State of New York, have invented certain new and useful Improvements in Embossing-Press Type and Strip Holders, of which the following is a specification.

This invention relates to embossing presses and methods of arranging the parts thereof for convenient operation, and in particular to an embossing press in which a single line or a plurality of lines of type are set up and used once or twice.

10 A particular object of the invention is to provide a type holding device in connection with a sliding base which will be automatically brought into position to be operated upon by the press.

15 A further object of the invention is to provide a work holding device which is adapted to hold different sizes of strips upon which the embossing is performed.

20 Referring to the drawing wherein I have shown a preferred embodiment of my invention;

25 Figure 1 is a side view in elevation of the embossing press and type and work holding devices, the press head being shown in section.

30 Figure 2 is a top plan view of the press and associated parts, as seen in Fig. 1.

35 Figure 3 is a section taken on the line 3—3 of Figure 1 showing the press parts in elevation and work holder and type holder in section.

40 Figure 4 is an enlarged partial top plan view of the press bed and work carrying table, the type carrier being removed.

45 Figure 5 is a side view in section through the press, the work table being positioned beneath the pressing element.

50 Figure 6 is a section taken on the line 6—6 of Figure 2, and

55 Figure 7 is a perspective view of a piece of embossing type.

Referring to the drawing in detail 5 indicates the head housing and 6 the bed of an embossing press, the head 5 being constructed to accommodate in its upper end a cross shaft 7 the outer end of which beyond the head 5 is provided with an operating handle 8 whereby the same may be revolved to operate the eccentrics 9 around which are positioned the strap like ends 10 of the vertically disposed plunger operating

and carrying rods 11 which pass through suitable guide bores 12 in the housing 5 and are secured at their lower ends to the presser head or plunger 13, which operates within the sides of the housing. The housing 5 may be cast integrally with the bed 6 or it may be bolted thereto.

60 The bed 6 is provided with grooves 14 in which fit the projections 15 depending from the underside of the work carrier table 16 to guide the work table in its sliding movement on the press bed from and towards the operating head of the press.

65 The sides of the press bed 6 are provided with plates 17 having cam faces 18 over which slide the cam blocks 19. The cam faces 18 of the plates slope downwardly towards the head of the press, so that when the blocks 19 are moved toward the press they will ride down the plate faces 18 and consequently lower the type carrier 20 which extends across the work table and is releasably attached at its ends to the tops of the cam blocks 19 through the medium of dowel pins 21 carried on the upper edge of said blocks which pass through suitable openings in the type carrier.

70 The upper ends of the cam blocks 19 are provided with flanges 22 which limit their downward movement by coming to rest on the upper edges of the guide brackets 23 which are secured to the sides of the work table 16 by suitable screws. When the flanges 22 are so positioned the type is in contact with the strip to be embossed.

75 The type carrier 20 comprises two bars 25 and 26, the bar 25 having a channel 27 cut therein the bottom of which is rounded as at 28, to fit into a matching groove or 80 cut out 29 in each piece of type 30. The channel is wide enough to accomodate a piece of type so that when the bar 26 is locked in position against bar 25 the type will be securely locked in the channel 27. 85 Any particular line of type may be held in the type bar. In order to release the type I provide for moving the bar 26 away from bar 25 by mounting the bar 26 on two headed pins 31 which are secured in 90 each end of bar 25 and are sufficiently long to allow of movement of bar 26 away from bar 25. In order to lock the bars together securely, I provide hook members 32 pivoted to the ends of bar 25 and adapted when 95 swung to have their hooked ends engage over the ends of bar 26.

Thus, it will be seen that as the work table 16 is moved along the press bed 6, the type carrier is gradually lowered until the type rests upon the material to be embossed beneath the press head 13, at which time the handle 8 is drawn forward, and the head 13 bears down on the type with sufficient pressure to cause embossing by the type dies or type. This lowering movement, as has been stated is caused by the riding of the cam blocks 19 down the cam faces 18 of the plates 17. When the work table is in the position shown in Figure 2 the type carrier and type are in spaced relation with the work table and the work can readily be removed.

In this particular machine the work comprises the embossing of strips of heavy composition, the embossing consisting of cutting paper letters out of a sheet and embossing them onto a strip in a single operation, the details of which are not set forth in this application, sufficient to say that some means must be provided for positioning strips of different lengths on the work table 16 beneath the type dies 30 and I provide retaining plates or work holders 33 adapted to be set on the table 16 over dowel pins 34, the plates being held in proper position through the medium of screws 35 which pass through slots 36 in the plates 33 and engage the table.

The plates 33 are provided with cut-outs 37 into which the opposite ends of the strip 38 fit and are held to be embossed by the dies or type 30.

Any particular size of cut out 37 may be provided in the plates 33 to accommodate strips 38 of various widths, and the positioning of the plates various distances apart allow for different lengths of strips.

It will be evident, therefore that I have provided a press for embossing strips of material which is simple in operation, has few parts and one which will perform the work on various sizes of strips with but few changes in the strip holding part of the press.

Having described my invention what I claim is:

1. In an embossing press, a pressing head, an embossing type carrier, a work carrying table movable toward and away from said head, and means for raising and lowering the type carrier automatically during movement of said table.

2. In an embossing press, a pressure exerting head, a work holder, an embossing

type carrier said work holder being movable toward and away from said head, and means for automatically lowering the type carrier when the work holder is advanced toward said head.

3. In an embossing press, a pressure exerting head, a work holder, an embossing type carrier, the work holder being adapted to be advanced and retracted relatively to said head, and means for automatically raising the type carrier off of the work holder during a retractile movement of said holder.

4. In an embossing machine a pressure exerting head, a movable work carrier, a type carrier slidably associated with the work carrier, a press bed, cam members associated therewith, and means on said type carrier engaging the cam members whereby a horizontal movement of the work carrier will result in a vertical movement of the type carrier.

5. An embossing press comprising a press bed, a pressure exerting head, a work carrier movable to a position beneath said head, means on said carrier for retaining a strip of material in position to be operated upon by said head, a type carrier movably associated with said work carrier and so arranged that the type in the carrier is positioned over said strip, and means on the press bed for causing contact of the type in the carrier with said strip when the carrier is moved to a position beneath said head.

6. An embossing press comprising a base, a work carrier slidable on said base, plates on said carrier having slots therein in which are held a strip of material to be embossed, an embossing type holder carried by said work carrier and vertically slidably relatively thereto, whereby the type may be raised and lowered relatively to the strip and means for limiting the downward movement of said type carrier.

7. An embossing press comprising a pressing head, a base, a work carrier slidable on said base, means for retaining the material to be operated upon in position on said carrier, cam members on the base, an embossing type holder carried by said work carrier, having depending portions which engage said cams so that when the work carrier is moved towards the pressing head the type holder will be lowered to bring the type into contact with the strip at a point beneath said pressing head.

BRYANT L. AKINS.
